UNITED STATES PATENT OFFICE.

JOHN DEAM KNEEDLER, OF SIOUX CITY, IOWA.

ROAD-BED EQUIPMENT.

No. 806,151.

Specification of Letters Patent.

Patented Dec. 5, 1905.

Application filed September 20, 1905. Serial No. 279,343.

To all whom it may concern:

Be it known that I, JOHN DEAM KNEEDLER, a citizen of the United States, residing at Sioux City, in the county of Woodbury and State of Iowa, have invented certain new and useful Improvements in Road-Bed Equipment; and I do hereby declare the following to be a full, clear, and exact description of the invention, such as will enable others skilled in the art to which it appertains to make and use the same.

My invention relates to road-beds for railways and to means for securing ties thereto; and it is more particularly an improvement upon devices described and claimed by me in Patent No. 795,622, granted to me on July 25, 1905.

The object of the invention is to provide a road-bed formed of a plurality of supporting-blocks formed of cement or other like material suitably reinforced.

A still further object is to provide means for securely fastening the rail-engaging plates to the tie, said fastening means being prevented from working through the artificial-stone supporting-blocks and serving to hold the tie against longitudinal movement upon said blocks.

With the above and other objects in view the invention consists of certain novel features of construction and combination of parts, the preferred form whereof will be hereinafter more clearly described, and pointed out in the claims.

In the accompanying drawings I have shown the preferred form of my invention.

In said drawings, Figure 1 is a perspective view of one of the blocks constituting my improved road-bed, a portion of a tie and a rail being shown secured thereto. Fig. 2 is a longitudinal section therethrough. Fig. 3 is a longitudinal section through the block, showing the reinforcing device embedded therein; and Fig. 4 is a detail view of one of the rail-engaging plates.

Referring to the figures by numerals of reference, 1 is a supporting-block formed of cement or other like material, the same being preferably oblong in form and having rectangular extensions 2 projecting from the centers of opposite sides thereof. The block 1, as well as its lateral extension 2, has channels 3 formed longitudinally in the bottom faces thereof, and the channels of the extensions and block communicate and have converging walls. Embedded within the block

and its extensions 2 are reinforcing-rods 4, formed of metal, preferably provided with retaining-barbs 5. Any desired number of these reinforcing-rods may be utilized, and they can be disposed in any preferred relation to each other. They extend throughout the length and width of the block and its extensions and maintain equal strength in all parts of the block and prevent it from cracking through the action of frost or the pounding of car-wheels.

A groove 7 is formed longitudinally with in the upper face of the block 1 and is adapted to receive one end of a metallic tie 8, which is preferably formed of a strip of metal. The upper surface of this tie lies flush with the upper surface of the block 1, and the rail 9 is adapted to rest thereon and upon the block and its extensions 2. The rail is held in place by means of clamping-plates 10, which fit snugly against the web and the base-flanges of the rail and are fastened thereon by means of a bolt 11, which extends through slots 12, formed within the plates 10. Tongues 13 extend from the clamping-plates and are adapted to rest upon the tie 8 when the rail is in position thereon. Each of these tongues has apertures 14, which receive the screw-threaded ends 15 of bolts 16, which extend vertically through the block 1. A reinforcing-plate 17 is preferably disposed within the channel 3 of block 1, and the bolts 16 through this plate and their heads 18 bear thereagainst. The bolts 16 are secured in place by means of nuts 19, and by tightening these nuts the plate 17 is drawn tightly against the lower surface of block 1, while the tongues 13 of clamping-plate 10, as well as the tie 8, are firmly secured upon the upper portion of the block by the same means.

In constructing a road-bed with devices such as herein described the blocks 1 are disposed at desired intervals, and soil is tamped around them and within channels 3, so that said blocks will be securely held against displacement. The ties 8 are then placed within the grooves 7 and upon bolts 16, and after the rail has been properly located the clamping-plates 10 are bolted thereon and placed in engagement with the bolts 16. Said bolts are then tightened by means of their nuts 19, and all parts of the device will be securely fastened together. The slots 12 in the clamping-plates allow for the expansion and contraction of the rails. The reinforcing-plates 17 constitute a durable

seat for the heads 18, and it is not possible, therefore, for said heads to work through the cement block after constant use. As the fastening-bolts 16 extend through the block 1, 5 they not only serve to secure the tie and the clamping-plates to the block, but they also prevent the tie and the rail mounted thereon from moving laterally.

Having thus fully described my invention, 10 what I claim as new, and desire to secure by Letters Patent, is—

1. A block for road-beds formed of artificial stone and having intersecting channels in one face, metallic reinforcing-rods embedded within the block and disposed at right angles to each other, said rods having projections thereon, and a tie-receiving groove disposed longitudinally within one face of the block.

2. The combination with an artificial-stone supporting-block having a channeled groove in one face thereof; of a tie set in one face thereof and flush with the surface of the block, a reinforcing-plate contacting with 25 the opposite face of the block, a tie-securing device extending through the plate and block and seated at one end upon the plate.

3. The combination with an artificial-stone supporting-block having intersecting channels in one face and a groove in its opposite face; of a tie set in the groove and flush with the surface of the block, a reinforcing-plate within one of the channels, rail-clamping plates upon the tie, and securing devices extending through the reinforcing-plate, the block, tie and clamping-plates and bearing one end upon the reinforcing-plate.

4. The combination with an artificial-stone

block having lateral extensions, said extensions and block being provided with intersecting channels and a groove within the block; of a tie seated within the groove and flush with the block, a reinforcing-plate within the channel in the block, rail-clamping plates mounted upon the tie and adapted to 45 secure the rail upon the block and its extensions, and securing devices extending through the block and tie and through the reinforcing and clamping plates said devices bearing upon the clamping-plate.

5. A device of the character described comprising an artificial-stone supporting-block having reinforcing-rods embedded therein and provided with extensions, said block having a channel and a groove in opposite faces, a reinforcing-plate within the channel, a tie within the groove, and securing devices extending through the block and tie and engaging and adapted to bear upon the plate.

6. A device of the character described comprising an artificial-stone supporting-block having metallic reinforcing-rods embedded therein and a channel and groove in opposite faces, a reinforcing-plate within the channel and headed bolts extending through the plate and block and extending into the groove, the heads of said bolts bearing upon the plate and the opposite ends of the bolt adapted to engage a tie within the groove.

In testimony whereof I have signed my name to this specification in the presence of two subscribing witnesses.

JOHN DEAM KNEEDLER.
